UNITED STATES PATENT OFFICE

2,520,182

ELECTRON DISCHARGE APPARATUS

Stanley Gordon Tomlin, London, England, assignor, by mesne assignments, to International Standard Electric Corporation, New York, N. Y., a corporation of Delaware

Application September 18, 1942, Serial No. 458,806
In Great Britain December 24, 1940

Section 1, Public Law 690, August 8, 1946
Patent expires December 24, 1960

2 Claims. (Cl. 250—27.5)

1

This invention relates to electron discharge apparatus utilising the principles of electron velocity modulation and consists in a modification of the invention claimed in United States patent application Serial No. 457,800 filed September 9, 1942, now Patent No. 2,421,043.

The present invention consists in a frequency changing apparatus for very high frequencies employing the principles of electron velocity modulation comprising a tube including an electrode system for generating an electron beam and directing it through gaps in a high frequency resonator, a grid electrode and a collector electrode in the path of the beam and means for maintaining the electrodes at such potentials that the operating condition of the tube is at a curved part of the grid-voltage collector-current characteristic, in which by adjustment of the beam velocity the device is caused to generate oscillations at a frequency slightly different from that of the source of applied waves, whereby the collector electrode current has an intermediate frequency component.

Another feature of the invention consists in a frequency changing apparatus for very high frequencies employing the principles of electron velocity modulation comprising a tube including an electrode system for generating an electron beam and directing it through gaps in a high frequency resonator, a collector electrode, means for maintaining the electrodes at such potentials that the operating condition of the tube is at a curved part of the collector-current collector-voltage characteristic, in which by adjustment of the beam velocity the device is caused to generate oscillations at a frequency slightly different from that of the applied waves, whereby the collector electrode current has an intermediate frequency component.

In carrying out the invention, similar apparatus to that described in the said prior application is employed.

The above mentioned and further objects and advantages of the invention and the manner of attaining them will be more fully set forth in the following description taken in conjunction with the accompanying drawings in which

Fig. 1 is a longitudinal section, partly diagrammatic of an electron discharge device in accordance with my invention

Fig. 2 is a diagrammatic cross-section of the device shown in Fig. 1 and

Fig. 3 is a curve illustrating the operation of the device.

Referring to the figures coaxial conductors 1

2

and 2 form a resonator of adjustable length, a coaxial line 3, 4 terminating in a loop 5 serves to feed incoming waves to the resonator. A cathode or electron gun 6 projects a beam of electrons past focussing and accelerating electrodes 7, 8 through apertures 9, 10 in the conductors 1 and 2 at the point of a voltage anti-node. Fins 11 are provided to reduce the gaps between the conductors at the apertures. The electrons are modulated in velocity in passing the gaps between the conductors. Beyond the resonator, and in the path of the beam, is a wire mesh grid 12 maintained at a relatively low potential approximately cathode potential and a collecting electrode 13 maintained at a suitable potential positive with respect to the cathode. The resonator is designed so that the gaps A and B between the inner and outer conductors are small in order that the transit time across a gap is small compared with a period of an oscillation of the applied waves and the diameter of the inner conductor is such that the transit time of electrons in moving from the centre of the first gap to the centre of the second gap is an odd number of half periods of the applied frequency.

If the transit time of electrons travelling from the resonator to the grid electrode is suitably adjusted, owing to the reflection of electrons from the low potential grid electrode, the valve will generate oscillations. For a given apparatus, the frequency of oscillation may be varied by adjustment of the resonator tuning and of the beam velocity, the latter regulating the electron transit times.

Now assuming that the resonator is tuned to resonate at the frequency (W_1) which it is desired to receive, and the apparatus is caused by adjustment of the beam velocity to generate oscillations at a frequency (W_2) slightly different from that of the received waves, then the voltage existing across the gaps A and B in the resonator may be represented by:

$$V_A \sin W_1 t + V_B \sin W_2 t \quad (1)$$

Thus electrons passing through the resonator will be velocity modulated by a potential of this form and a graph showing the modulation velocity would be a beat frequency curve.

The intermediate frequency is detected by a frequency component detector 14 coupled to the collector electrode 13.

The production of an intermediate frequency from such a beam of electrons depends upon the grid-voltage collector-current characteristic. This curve is of the form shown in Fig. 3 where

the collector current is plotted against the static potential of the grid. We may regard the grid voltage changes as equivalent to velocity variations of the electron beam, at least in a first approximation, and thus we see that the collector current is a non-linear function of the velocity modulation of the beam. Hence, when the beam is modulated by a potential of the form of the Equation 1 the collector current will have a component of the form:

$$I = I_0 \sin (W_1 - W_2)t \quad (2)$$

i. e. the collector current has an intermediate frequency component which may be fed into a standard intermediate frequency amplifier followed by a detector and of necessary audio frequency output stages.

In practice an intermediate frequency of 10 megacycles has been obtained when receiving 200 cm. waves. Further it has been found that the intermediate frequency can be varied by about 1 megacycle for a fixed setting of the resonator by adjustment of the beam velocity.

A similar result may be obtained if as in the prior application, the grid electrode is omitted, and the collector electrode is maintained at approximately cathode potential. If the spacing of the collector electrode and the potentials applied to the electrodes are suitably chosen the tube may be caused to generate oscillations of a frequency slightly different from that of the applied waves. In this case the tube is arranged to operate on a curved part of the collector-current collector-voltage characteristic, and the collector current will have an intermediate frequency component.

What is claimed is:

1. A frequency changing device comprising an electron discharge tube including a high frequency resonator tuned to incoming waves, electron beam generating means positioned adjacent said resonator to project a beam of electrons in a path through said resonator, means coupled to said resonator for applying the incoming waves, a collecting electrode positioned in the path of said beam adjacent said resonator for collecting electrons from said beam, means coupled to said electrode for applying biasing potential thereto, a reflecting electrode mounted between said res-

onator and said collecting electrode and positioned at a distance from said resonator providing an electron transit time from said resonator to said reflecting electrode such that electrons reflected therefrom cause said resonator to oscillate at a frequency slightly different from the frequency of the incoming waves whereby reflected electrons cause said resonator to oscillate at said slightly different frequency, and output means coupled to said collecting electrode for detecting the frequency component of said electrode current which is the beat frequency between the frequency of the incoming waves and that of the oscillating resonator.

2. A frequency changing apparatus according to claim 1 in which said resonator comprises a coaxial line provided with diametric apertures in the inner and outer conductors at a field anti-node through which apertures the electron beam is adapted to be projected, the length of said coaxial line being adjustable to tune the resonator to the applied high frequency waves.
